UNITED STATES PATENT OFFICE.

WILLIAM F. DELZER, OF MILWAUKEE, WISCONSIN.

LAUNDRY DRIER.

Application filed February 9, 1924. Serial No. 691,656.

To all whom it may concern:

Be it known that I, WILLIAM F. DELZER, a citizen of the United States, and resident of Milwaukee, in the county of Milwaukee and State of Wisconsin, have invented certain new and useful Improvements in Laundry Driers, and I do hereby declare that the following is a full, clear, and exact description thereof.

10 This invention relates to laundry driers.

In laundry driers, as heretofore constructed, it has been found necessary to bring in fresh air in addition to the products of combustion furnished by the burners, and 15 to continuously remove the air from the drier. However, in driers as previously constructed, it frequently happened that the incoming fresh air did not become heated before it contacted with the clothes, and consequently the clothes were not subjected at 20 all portions to heated air, and therefore the drying was greatly retarded.

This invention is designed to overcome the above noted defects, and objects of such 25 invention are to provide a laundry drier in which the incoming fresh air is caused to pass through the flame, or the highly heated products of combustion, and to intimately mix therewith prior to the time that it reaches the clothes; to provide means whereby the heated air is caused to contact 30 with the clothes and the air removed from the apparatus is merely that which has previously been used and from which the major 35 portion of the heat has been extracted.

Further objects are to provide a simple 40 construction adapted to fit a standard type of laundry drier and to so organize the parts that the means for bringing in the fresh air is heated from the burner and also uniformly distributes the air throughout the length of the elongated burner.

An embodiment of the invention is shown 45 in the accompanying drawings, in which:

Figure 1 shows one form of laundry drier embodying the invention.

Figure 2 is a sectional view on the line 2—2 of Figure 1.

Figure 3 is an enlarged sectional view on 50 the line 3—3 of Figure 2.

Figure 4 is a longitudinal, sectional view through the means for bringing in the fresh air, showing it associated with the burner and with the front plate of the drier.

55 The body of the laundry drier may be of

the usual form and comprises an upright casing 1 of sheet metal provided with one or more slidably mounted doors carried in any suitable manner, as from upper suspension members 3. The doors 2 may be formed 60 in the conventional manner and may carry a plurality of rods upon which the clothes are hung. This is the usual construction, and a detailed explanation and showing is not thought necessary, as the specific construction forms no portion of this invention.

Below the doors a front plate 4 is positioned and is secured to the face of the device in any suitable manner, by means of rivets 5, bolts, or other securing means. It 70 is provided with an aperture through which an elongated burner 6 projects. Above the burner a window 7 of mica, glass, or other transparent material, is provided. Below the burner 6 a triangular opening is formed 75 and if desired may be provided with a plurality of vertical slats, or cross-bars 8, as shown in Figures 1 and 3. This triangular opening is surrounded by an inwardly projecting triangular flange 9. A hollow 80 triangular shaped member 10 of sheet iron fits over the flange 9 and conforms thereto. This member 10, as may be seen from Figures 2 and 4, extends substantially the entire length of the drier and is closed at its rear end. It is provided with a plurality of regularly spaced apertures 11 positioned on each side of the member through its slanting walls and opening in close proximity to the burner. The burner 6 is provided with 85 a plurality of apertures 12 from which the flames are projected. These apertures in the burner are directed slightly downwardly and outwardly, as shown in Figures 3 and 4.

If desired, a strap 14 may surround the 95 rear portion of the member 10 and may engage the burner 6 to hold these parts in their correct relative position, (see Fig. 2).

The air, after it has been used, is removed 100 from the apparatus by means of a pair of apertured pipes 13 located adjacent the bottom of the drier and upon opposite sides. These pipes lead out from the drier and are connected with a suitable flue.

The operation of the apparatus is as follows:—The burner, having been lighted, will 105 project a series of flames downwardly into proximity of the slanting walls of the member 10 and the heat radiated from such flames will heat such member and conse- 110
